UNITED STATES PATENT OFFICE.

JOHN E. MEYER, OF NEW YORK, N. Y.

WINE-COOLER.

SPECIFICATION forming part of Letters Patent No. 705,270, dated July 22, 1902.

Application filed April 22, 1902. Serial No. 104,146. (No model.)

To all whom it may concern:

Be it known that I, JOHN E. MEYER, a citizen of the United States, residing at New York city, State of New York, have invented certain new and useful Improvements in Wine-Coolers, of which the following is a specification.

My invention relates to that class of coolers for champagne and other bottled liquors in which an ice-receptacle is employed having a bottle-chamber within the same into which the bottle may be inserted and from which the same may be withdrawn without the necessity of removing or disturbing the ice.

The object of the invention is to provide means whereby a greater cooling effect of the ice upon the wine in the bottle-chamber may be obtained and means whereby the bottle-chamber may be increased or decreased in length.

A further object of the invention is to provide means whereby the bottle-chamber may be rotated within the ice-receptacle for the purpose of rapidly cooling the bottled wine contained therein and means whereby the water into which the ice melts may be readily withdrawn.

Other objects and advantages of the invention will hereinafter appear, and the novel features thereof will be set forth in the claims.

In the drawings forming part of this specification, Figure 1 is a vertical section of a cooler constructed in accordance with my invention. Fig. 2 is a top plan view of the same with the cover removed, and Fig. 3 is a detail sectional view.

Like reference-numerals indicate like parts in the different views.

The body 1 of the cooler is in the form of a tub, having a closed bottom 2 and an open top. The same is preferably constructed of metal, although it may be made of any other suitable material. On opposite sides thereof and near its upper end the body is provided with lugs or ears 3, to which are attached the ends of a bail 4, constituting a handle, by means of which the device may be carried from point to point. The open upper end of the body 1 is adapted to be closed by a lid or cover 5, having a knob or handle 6 thereon. The said lid or cover fits closely within the open end of the body 1 and may be constructed of wood

or any other suitable material. I prefer, however, to make the same of the same metal as that from which the body 1 is made, in which case said cover is hollowed out, so as to form an air-chamber.

Secured within the body 1 of the cooler is a perforated false bottom 7, the same being located a short distance above the main bottom 2, as shown. The said false bottom is supported around its outer edges upon the ring 8 and may also be soldered directly to the inner surface of the body 1. The false bottom 7 may be made of any open-work material, but is preferably constructed of sheet metal having perforations at intervals therein. Leading from the space beneath the false bottom 7 is a drain-cock 9, by means of which the water contained in the bottom of the body 1 may be drawn off.

Cooperating with the parts just described is a cylindrical bottle-chamber 10, located centrally within the body 1 and supported upon the false bottom 7. The walls of the bottle-chamber 10 are constructed of perforated sheet metal, wire-netting, or other reticulated material, and the bottom 11 of said chamber is swiveled, as shown at 12, to the false bottom 7, so that said chamber is capable of axial rotation. The chamber 10 is braced, guided, and maintained in vertical position by means of the rings 13 14, which surround the same near its upper and lower ends, respectively, and are connected by the brace rods or arms 15 16 to the inner sides of the body 1. The chamber 10 fits loosely within the rings 13 and 14, so that there is no binding between these parts, and consequently the rotation of the bottle-chamber 10 is unimpeded by these rings.

To provide for the extension and contraction of the bottle-chamber 10, the same is made of a plurality of telescoping sections, the lower section 17 fitting and moving within the upper section 18. To prevent the collapse of the two sections of said chamber when the same are in their extended positions, I secure to or form upon the lower end of the upper section 18 the shoulders or stops 19 and mount upon the upper end of the lower section 17 the outwardly-spring-pressed hooks or catches 20. The upper ends of said hooks or catches 20 are adapted to engage the

lower ends of the shoulders or stops 19 to hold the sections 17 and 18 in their extended positions, but are also adapted to be forced inwardly into sockets or openings 21 in the 5 lower section 17, so that said lower section may telescope within the upper section 18 when the latter is forced downwardly.

In using my improved cooler broken ice is placed within the annular ice-receptacle 10 which surrounds the bottle-chamber 10, and the bottle of wine to be cooled is placed within said bottle-chamber. The heat of the wine will be absorbed by the ice, reducing the temperature of the former and melting the latter. 15 The cooling effects of the ice are utilized to the best advantage by providing means for enabling the water to pass off, and thus have constantly-exposed fresh surfaces of ice. As the ice melts a portion of the water will 20 pass through the perforations in the walls of the bottle-chamber 10 into contact with the outer surface of the bottle and thence pass downwardly through the bottom 11 of said chamber and through the false bottom 7 into 25 the space beneath said false bottom, while other portions will pass directly through said false bottom into the space beneath the same. From the latter space this water may be readily drawn off through the drain-cock 9. During 30 all this time the cover 5 remains in place upon the upper end of the body 1 and prevents the melting of the ice from outside heat. When the bottle being cooled is empty or it is desired for any reason to remove the same, 35 it is merely necessary to take off the cover 5 and lift the bottle out of the chamber 10, in which it is located. The same may then be reinserted or a fresh bottle substituted therefor. All this may be done without removing 40 or disturbing the ice in the ice-receptacle, and a great economy, as well as a great convenience, is thereby effected. If it be desired to cool a bottle of wine quickly, it may be done by placing it within the chamber 10, surround- 45 ed by ice, and rotating said chamber on its swivel connection 12 with the false bottom 7. The telescoping sections 17 and 18 of the bottle-chamber 10 provide for the collapse of this chamber into compact form for packing or 50 storage. Their principal purpose, however, is to enable the bottle-chamber to be increased and decreased in length for the accommoda- 55 tion of bottles of different heights. With a single small bottle the chamber 10 will be used in its contracted condition. When a large bottle or more than one is to be cooled, the chamber 10 will be used in its extended condition.

Having now described my invention, what

I claim as new, and desire to secure by Letters Patent, is—

1. In a wine-cooler, a body constituting an ice-receptacle, a perforated false bottom therein, a cylindrical foraminous bottle-chamber mounted for rotation within said receptacle 65 on said false bottom, and means for drawing off the water from the space beneath said false bottom.

2. In a wine-cooler, a body constituting an ice-receptacle, a perforated false bottom therein, a cylindrical foraminous bottle-chamber having a swivel connection with said false bottom, and means for drawing off the water from the space beneath said false bottom. 70

3. In a wine-cooler, a body constituting an ice-receptacle, a perforated false bottom therein, a cylindrical perforated bottle-chamber mounted for rotation within said receptacle on said false bottom, rings surrounding said chamber at its upper and lower ends, and 80 bracing-arms connecting said rings with said body. 75

4. In a wine-cooler, a body constituting an ice-receptacle, a perforated false bottom therein, a cylindrical, foraminous bottle-chamber 85 within said receptacle having a swivel connection with said false bottom, guide-rings embracing said bottle-chamber at different points, and a drain-cock leading from the space beneath said false bottom. 90

5. In a wine-cooler, an ice-receptacle, and a cylindrical bottle-inclosing chamber therein made up of a plurality of telescoping sections.

6. In a wine-cooler, an ice-receptacle and 95 a rotary foraminous bottle-chamber therein made up of a plurality of telescoping sections.

7. In a wine-cooler, an ice-receptacle, a cylindrical bottle-inclosing chamber therein made up of a plurality of telescoping sections, 100 and spring-catches for preventing the collapse of said sections, when extended.

8. In a wine-cooler, an ice-receptacle, a cylindrical bottle-inclosing chamber therein made up of a plurality of telescoping sections, 105 and outwardly-spring-pressed catches connected to one of said sections and adapted to engage the other for positively locking said sections against inward movement, and thereby preventing the collapse of said sections, 110 when extended.

In testimony whereof I have hereunto set my hand in presence of two subscribing witnesses.

JOHN E. MEYER.
